UNITED STATES PATENT OFFICE.

AUGUSTUS I. SIESEL, OF NEW YORK, N. Y., ASSIGNOR TO MAX G. COHN & CO., INC., OF NEW YORK, N. Y.

SPECTACLE-TEMPLE.

1,182,429.

Specification of Letters Patent.

Patented May 9, 1916.

Application filed February 12, 1915. Serial No. 7,679.

To all whom it may concern:

Be it known that I, AUGUSTUS I. SIESEL, a citizen of the United States, and a resident of New York, in the county of New York and State of New York, have invented certain new and useful Improvements in Spectacle-Temples, of which the following is a specification.

This invention relates to improvements in spectacles, goggles and like lens carrying or other protective devices for the eyes, and of that type supported partially by the nose and held in relative position by temples extending past the ears.

15 One object is to provide temples that are so readily pliable that they can be adjusted in shape and length to obtain the most satisfactory results and easily bent by the fingers of the wearer to conform to the shape 20 of the ears.

Another object is to provide such temples having an exterior which is at once impervious to, and unaffected by, perspiration, moisture, oils or other skin and hair emanations, that is a non-conductor of heat, therefore being always comfortable when in contact with the skin, presenting a smooth surface of relatively large area which neither abrades nor irritates the skin or affects the 30 circulation of blood or nerve ganglia at the back of the ear.

A further object is to provide riding temples of non-metallic exterior in close imitation of such frame material as tortoise-shell, 35 horn, etc., having a reinforcement so arranged that both parts are attached to the spectacle frame as a unit and which may be bent almost unlimitedly without breaking.

40 A still further object is to provide temples which are so peculiarly light and satisfactory as to avoid the usual resort to unsanitary and unsightly windings of fabric, rubber, chamois and the like in order to be 45 acceptably worn without actual discomfort.

These and other objects are attained by the novel construction and arrangement of parts hereinafter described and shown in the accompanying drawings, forming part 50 of this specification, and in which:—

Figure 1, is a perspective view of a spectacle temple bent to conform to the exterior contour of the back of an ear. Fig. 2, is an enlarged fragmentary side view of 55 the same at its connection with the bow

frame. Fig. 3 is a plan view of the same. Fig. 4 is a longitudinal section of the temple. Fig. 5 is a fragmentary perspective view of the enveloping strip. Fig. 6 is an enlarged cross sectional view taken on line 60 6—6 of Fig. 3, and, Fig. 7 is a similar sectional view on line 7—7 of Fig. 2.

The construction of the temple comprises the use of a narrow strip of celluloid or horn 10, colored to represent the material 65 of which the spectacle frame 11 is constructed and folded by mechanical processes to envelop the temple reinforcement 12, which, as indicated, consists of a wire of great pliability and strength.

The end 14 of the strip is formed in dies 70 so as to completely cover the inclosed reinforcing wire which is formed preferably with a ball point 15 at one end and a flattened portion 16 near the other, the same 75 having a central perforation 17 to receive the pivot joint pin 18, used in connecting the temples 20 with the hinge jaws 19 of the spectacle frame 11, the extreme end 21 of the temple extending past the joint and 80 making contact with the frame in such manner as to give a spring effect to the temples causing them to press against the sides of the head slightly thereby assisting in holding 85 them in position.

The edges of the strip are united and caused to permanently adhere together by means of a suitable binding cement, which is applied not only to the edges, but over the entire interior area causing it to become 90 securely affixed to the reinforcement there- 95 within. In order to resist any tendency of the covering to separate from the wire it may be roughened or slightly corrugated so that it will be firmly embedded and not crack or pull off except considerable force be used. After the joint has been made and the cement set the surface is polished and the temples assembled as usual.

I am aware that tubular coverings have 100 been used prior to this invention but the same do not adhere to the core and are easily stripped off when the end fastenings become loosened, hence I do not broadly claim a covered wire, but

105 What I do claim as new and seek to secure by Letters Patent, is:—

1. A temple wire comprising a pliable non-metallic casing, a corrugated flexible core contained therein and means for caus- 110

ing said casing to firmly adhere to said core.

2. A temple wire comprising a non-metallic casing, a rough surfaced reinforcing element embedded therewithin over its entire area and a joint pin passing through both casing and reinforcing element.

3. A wire temple comprising a non-metallic casing, a corrugated reinforcing element wholly embedded therewithin by the

application of external pressure and a cement between said casing and said reinforcing element.

In testimony whereof I have signed my name to this specification in the presence 15 of two subscribing witnesses.

AUGUSTUS I. SIESEL.
